UNITED STATES PATENT OFFICE.

FRITZ AXELSON, OF DENVER, COLORADO.

STARTING-CRANK SUPPORT.

Application filed September 14, 1925. Serial No. 56,171.

To all whom it may concern:

Be it known that I, FRITZ AXELSON, a citizen of the United States, residing at the city and county of Denver and State of Colorado, have invented certain new and useful Improvements in Starting-Crank Supports; and I do declare the following to be a full, clear, and exact description of the invention, such as will enable others skilled in the art to which it appertains to make and use the same, reference being had to the accompanying drawings, and to the characters of reference marked thereon, which form a part of this application.

15 This invention relates to improvements in devices for supporting automobile starting cranks.

Internal combustion engines are used almost exclusively for driving automobiles 20 as well as for many other uses and are therefore very common.

In order to start an internal combustion engine it must be rotated to some extent so as to get a charge of combustible mixture 25 into the proper cylinder and this is now accomplished by means of a suitable electric starter. It sometimes happens, however, that the starter becomes inoperative and the engine must then be manually rotated 30 through the medium of a crank. One maker of automobiles provides his cars with cranks that are always in place so as to be available when needed. Other automobile makers provide cranks that can be put into place 35 when needed, but which are normally carried in the tool box. When the crank is permanently attached to the machine, it sometimes becomes loose, due to the constant jarring to which it is subjected and it will then 40 be the cause of disagreeable noise. To prevent the crank from swinging and rattling, various devices have been tried with more or less success.

45 It is the object of this invention to produce a crank holder that shall be so constructed that it will be adapted to be located to the rear of the radiator and underneath the hood so that it will be entirely concealed under normal conditions and which can be 50 readily applied without the use of special tools. It is a further object to produce a device of this type that shall be exceedingly simple and which can therefore be cheaply constructed.

55 In order to describe my invention so that it can be readily understood and to explain

the manner of constructing and using the same, I shall have reference to the accompanying drawing in which the preferred embodiment has been illustrated and in which:

60 Fig. 1 is a perspective view of the front end of an automobile showing the position in which the crank is held by means of my invention;

65 Fig. 2 is a plan view of the front end of a crank case showing the starting crank in place and held against movement by means of my invention; parts of the members shown being broken away so as to better disclose the construction;

70 Fig. 3 is a longitudinal section taken on line 3—3 Fig. 2;

Fig. 4 is a transverse section taken on line 4—4 Fig. 2;

75 Fig. 5 is a perspective view of my device, and

Fig. 6 is a side elevation showing a modified form of my invention.

80 Numeral 1 designates the front end support of a crank case such as employed in connection with a well known make of automobile. As the engine has a three-point suspension, the tip of this case is provided with a tubular portion 2 that is journaled in a box 3 on the chassis frame. Secured 85 within this tubular journal is a bushing 4 which serves as a bearing for the straight portion 5 of the crank 6. This bushing is made longer than the tubular member 2 through which it extends and projects rearwardly for a distance of about one inch 90 (Figs. 2 and 3). Secured to the inner end of the crank arm 5 is a starting crank ratchet 7 that is held against movement with respect to the part 5, by means of a pin 8 95 that extends diametrically through the ratchet and the part 5. This pin has a head 9 and is held in place by a cotter pin 10. A spring 11 encircles the part 5 to the front 100 of the end support and tends to hold the crank in such a position that the shoulder 12 of the ratchet 7, abuts the rear end of the bushing 4 (Fig. 2). When the crank is employed for starting the engine, it is moved rearwardly, against the tension of the 105 spring 11, until it engages a pin on the crank shaft, but when it is not in use it is held in its forward position by the action of the spring 11. It is evident that if no means is provided to hold the crank in any 110 definite position that it will assume a position in which the crank arm hangs vertical

as this would be in accordance with the action of gravity. In order to hold the crank in any desired position and to prevent it from dangling and rattling, I have secured to the exposed rear end of the bushing 4 a member that I have designated as a whole by the numeral 13. This member has a cylindrical part 14 of an inside diameter which permits it to be slipped over the rear end of the bushing 4 and which is provided with a set screw 15 by means of which it may be clamped in place and prevented from relative movement with respect to the bushing. The rear end of member 13 has a portion 15 extending rearwardly to a point back of the head 9 of the bolt 8 (Fig. 3). The inner surface of part 15 is concave in the direction of the axis of member 13 and eccentric with respect thereto (Fig. 4). At the edge 17, the inner surface is spaced from the center and from the outer surface of the ratchet 7 a sufficient distance to permit the head to enter. Owing to the eccentricity, the distance between the inner surface of member 15 and the outer surface of the ratchet decreases in a counter clockwise direction (Fig. 4) and the head 9 can therefore move only a short distance before it will bind against the inner surface of member 15. It is now evident that the crank can move only a short distance in a counter clockwise direction (Fig. 4) before it is brought to a stop by the head 9 engaging the member 15. By properly adjusting the member 13 on the bushing 4, the crank can be held in the position shown in Fig. 1 or in any position between the vertical ones. The question of whether the crank will be held in the position shown with respect to the center of the machine (pointing to the right) or not is determined by the arrangement of the part 15. By reversing the direction of the inclination from that shown in Fig. 4 the crank would have to be rotated in the opposite direction in order to become locked. The part 15 is of such length that

it will not interfere with the proper use of the crank in starting the motor. My device can readily be applied and removed as it is only necessary to remove the ratchet member 7. When this is done member 13 can be put in place or removed. It will be seen from Fig. 5 that my invention is very simple and comprises a cylindrical portion (14) having an extension 15 projecting from one end, the inner surface of which is eccentric with respect to the axis of the cylindrical part. The inner surface of the projecting part 15 should preferably be concave in the direction of the axis so that the crank will be held against longitudinal movement as well as against rotary movement.

In Fig. 6 I have shown a modification in which the bushing 44 is formed with an extension 151 corresponding to the extension 15 on member 13. As the only difference between the embodiment shown in Fig. 5 and that shown in Fig. 6 is one of size, I shall not enter into any detailed description of the same.

Having now described my invention, what I claim as new is:

1. A device for holding a crank from rotating in one direction, which comprises, in combination, a member having an opening adapted to receive one end of a crank, a projection extending from one side of the crank and a member having an eccentrically arranged surface adapted to be engaged by the projection and to act as a stop against rotation in one direction.

2. An article of manufacture comprising a cylindrical body member, having an arcuate surface projecting from one end, said surface being eccentric with respect to the axis of the cylindrical portion and internally concave in the direction of the axis of the cylindrical member.

In testimony whereof I affix my signature.

FRITZ AXELSON.
